UNITED STATES PATENT OFFICE.

ENGÈNE SCHNEIDER, OF PARIS, FRANCE, ASSIGNOR TO SCHNEIDER & CIE., OF PARIS,
FRANCE.

FIELD-GUN CARRIAGE.

Specification of Letters Patent.

Patented July 29, 1919.

1,311,778.

Original application filed July 3, 1916, Serial No. 107,392. Divided and this application filed March 31, 1919. Serial No. 286,481.

To all whom it may concern:

Be it known that I, EUGÈNE SCHNEIDER, a citizen of the Republic of France, and a resident of Paris, France, have invented a new and useful Field-Gun Carriage, which invention is fully set forth in the following specification.

In my application Serial No. 107,392, filed July 3, 1916, of which the present application is a division, I have described and claimed a gun carriage in which there is a gun-supporting frame mounted to rotate about a vertical axis on a lower carriage frame and means for directing the fire of the gun with reference to fixed base lines or points, or for indirect aiming, thereby avoiding the necessity of taking a fresh sight for firing at any predetermined target within a given sector of horizontal range.

The present invention relates to a constructional form of the invention originally shown and described in my above application but not now specifically claimed therein, and comprises a gun carriage having an upper gun-supporting frame mounted to turn on a lower carriage frame and a special frame adjustable in respect to the gun-supporting frame, and also movable with the latter and adapted to receive a sighting device the longitudinal axis of which is arranged to pass through the vertical axis of rotation of the upper gun-supporting frame and, when prolonged, to pass through some selected sighting point, becomes a base line or auxiliary sighting line on which the sighting device is to be maintained during firing at any particular target.

In order that the invention may be more readily understood, reference is had to the accompanying drawings in which—

Figure 1 is a side elevational view of a gun carriage partly in vertical section on line 2—2 of Fig. 2 embodying my improvements;

Fig. 2 is a plan view of Fig. 1; and

Fig. 3 is a diagram illustrating the use of a field gun carriage provided with my improvements.

Referring to the drawings, A is a slide or cradle on which the gun barrel is mounted so as to be capable of sliding longitudinally therein. The cradle A is journaled on trunnions in the upper mountains B—B'—B of fork or stirrup shape, whose circular base

B' is adapted to revolve about a virtual vertical axis O on a concentric guide C' of the lower carriage C—C'—C. This lower carriage comprises a curved axle D having its center of curvature in a virtual vertical axis O which is the common center of the base B of the upper mounting and of the guide C'.

The upper mounting B—B'—B in pivoting about its virtual axis O, bears in front upon the curved axle D and at the rear upon the guide C' formed on the head of the lower carriage C—C'—C with which the carriage trail C² forms one piece. As shown, the trail C² is provided with an anchoring plate H provided with any suitable means permitting the trail to be adjusted transversely for correcting deviations from the line of aim due to successive firing.

The training mechanism for the upper gun-carriage mounting B—B'—B comprises a hand-wheel P fixed on a shaft p journaled in the upper mounting which actuates, through gearing p'—p²—p³—p⁴—p⁵—p⁶, a pinion Q. Q is a pinion carried by the upper mounting and engages circular rack 75 formed on the curved axle D, the upper side of which carries a graduated scale from which the various training angles can be read.

G is a sighting device mounted on a bracket arm F, S the lower end of which is made fast by a screw-stud s to a circular rack T concentric to and movable in the curved axle D. The stud s moves in a slot d' formed in the curved axle. The circular rack T has two series of rack teeth, namely, internal teeth t engaged by the pinion Q of the upper mounting, and the external teeth t'. By means of the external teeth t' the circular rack T with bracket arm S, F can be shifted along the hollow axle around the virtual axis of pivotatation O. For this purpose there is provided a removable hand-wheel N mounted on an axle U journaled in the lower carriage side-frame C. This axle 100 is provided with a bevel gear u which, through the train u', u², u³, v', v and worm V engaging the external rack t', moves the rack T.

It will be readily perceived that the motion 105 imparted by the hand-wheel N to the circular rack T, will be transmitted through the internal teeth t to the pinion Q which is

rendered stationary by any suitable known automatic jamming device not shown, and consequently to the entire structure constituted by the upper mounting and the gun barrel carried by the latter.

The training movements imparted by the hand-wheel P will in no way affect the position of the circular rack T, nor that of the bracket F for the sighting apparatus. The arrangement thus provides also a sighting means having an independent line of sight in the horizontal plane.

The device thus far described operates as follows:

- 15 Referring to diagram Fig. 3, before firing at given targets, the angles α , B, B', B² are measured by a theodolite or other angle-measuring device. The lower carriage having been brought into position and anchored 20 at the point α (Fig. 3) so as to cover a sector O—X— α^1 —X—O, then indirect firing is aimed upon any given target Y situated at any point of the sector, by placing the 25 sighting apparatus G on the bracket F and training the gun by sighting continuously any given auxiliary sighting point Z along the line O—Z, which incloses a constant angle α with a fixed directing line such as the line O— α^1 bisecting the angle subtended by 30 the arc X— α^1 —X. The angular relations of the lines of sight of the targets Y, Y¹, Y² to the base line O α as previously measured by any suitable means, and the values α —B, α —B', α —B² which give the angular 35 placement of these lines of sight with the fixed directing line of sight determined. The upper mounting B—B'¹—B is now successively trained by operating training wheel P about axis O on the lower carriage as indicated by the valves α —B, α —B', and α —B². The angle of fire required to hit targets Y,

Copies of this patent may be obtained for five cents each, by addressing the "Commissioner of Patents, Washington, D. C."

Y¹, Y² is thus obtained indirectly without the necessity of taking a fresh sight for firing as the target is changed.

Should the firing cause a deviation from 45 the correct training line, this error is corrected by adjusting the lower carriage trail across its anchoring-spade plate H.

What is claimed is:—

1. In a field gun carriage, the combination 50 of a lower carriage frame having a curved wheeled axle portion, a curved track movable along said curved axle and provided with a bracket arm adapted to receive a sighting device, an upper gun-supporting 55 frame supported on said lower frame and having operating connections with said track for training the gun about a center common to said curved axle and curved track, and means for shifting said track to keep the 60 sight of said sighting device set along a predetermined base or auxiliary sighting line through said common center.

2. In a field gun carriage, the combination 65 of a lower carriage frame having a curved wheeled axle portion, a curved rack having internal and external gear teeth and movable along said curved axle, a bracket arm adapted to receive a sighting device fast to 70 said rack, an upper gun-supporting frame supported on said lower frame and having gear connections with said rack for training the gun about a center common to said axle and rack, and manually-operated gear means 75 on said lower frame engaging said rack for keeping the sight of said sighting device set along a predetermined base or auxiliary sighting line through said common center.

In testimony whereof, I have signed this specification.

EUGÈNE SCHNEIDER.
